UNITED STATES PATENT OFFICE.

FRED RICKS AND ERNEST GEORGE BURGOYNE, OF LEICESTER, ENGLAND, AS-
SIGNORS TO UNITED SHOE MACHINERY CORPORATION, OF PATERSON, NEW JER-
SEY, A CORPORATION OF NEW JERSEY.

SEWING MACHINE.

Application filed April 2, 1921, Serial No. 457,931, and in Great Britain May 31, 1920.

This invention relates to hooked needle sewing machines for use in the manufacture of boots or shoes (hereinafter referred to generically as shoes) and it is more especially concerned with welt-handling mechanism in welt sewing machines.

The most highly developed form of welt sewing machine is equipped with devices which can be thrown into operation at the conclusion of sewing to advance a gripper to engage the welt near the sewing point and to sever the welt so held, releasing the shoe and retaining a hold on the end of the supply of welting, such devices being automatically operated at the beginning of a fresh sewing operation to move along the line of feed during the initial feed of the work by the machine and then to release the welt and retire to inoperative position.

In the use of machines so equipped it has been known to occur that the devices for holding and severing the welt (which are thrown into operation by a pull on the welt) have come into operation at some undesired time as, for instance, owing to a pull applied to the welt when the machine was stopped at some time other than at the completion of the sewing of a welt, and it is one object of the invention to provide means eliminating this source of possible inconvenience.

Again, the welt-holding gripper in a machine having these devices requires to have its lower jaw pivot adjusted if the thickness of welt sewn varies considerably in different classes of work, to maintain approximate parallelism of the jaws when closed on the welt and secure uniform gripping action. Another object of the invention is to eliminate as far as possible the need for adjustment in this respect.

Yet again, these devices have been so organized that the lower gripper jaw received upward (gripper-closing) movement only after the gripper had attained its advanced position, with the result that it has been known to occur that the lower jaw in moving upwardly, scraped along the surface of the shoe upper to the detriment of the latter. It is yet another object of the invention to overcome this disadvantage.

A feature of the invention contemplates the provision in a welt shoe sewing machine of power-operated mechanism for severing the welt dependent for operation upon the

performance of a plurality of separate operations on the part of the operator after the completion of the sewing operation.

Another feature of the invention contemplates the provision in a welt shoe sewing machine of means for holding the welt after the completion of the sewing operation comprising a pair of welt gripping jaws pivotally movable with relation to each other, one of which has welt engaging surface portions longitudinally inclined with relation to each other to enable the jaws to uniformly grip welts of different thicknesses.

Another feature of the invention contemplates the provision in a welt shoe sewing machine of power operated means for gripping the welt after the completion of the sewing operation comprising a pair of relatively movable welt gripping jaws, and means for advancing the jaws toward the welt, for partially closing the jaws during said advancing movement, and for causing the jaws to grip the welt at the end of the advancing movement, such closing of the jaws during their advancing movement preferably being sufficient to cause their ends to lightly engage the outer edge portion of the welt.

The above and other objects of the invention will become fully evident to those skilled in the art from the ensuing description of a preferred form of the invention as applied by way of example, to a welt sewing machine of the type illustrated and described in the patent to Topham No. 1,099,326.

In the accompanying drawings of this preferred form of the invention:—

Figure 1 is a front end elevation, partly in section, of a welt shoe sewing machine embodying the several features of the invention in their preferred form; Fig. 2 is a plan view, partly in section, of a portion of the front end of the head of the machine; Fig. 3 is a detail plan view, partly in section, showing the welt guiding and measuring devices and certain parts cooperating therewith; Fig. 4 is a side elevation, partly in section, of the welt engaging end of the welt cutting and holding device; Fig. 5 is a bottom plan view of the portion of the welt cutting and holding device illustrated in Fig. 4; and Fig. 6 is a detail sectional elevation of the welt measuring devices.

The machine illustrated in the drawings

is provided with the usual stitch forming devices comprising the curved hook needle 2, awl 4, and looper 5.

- The main shaft 6 of the machine is normally driven by a belt pulley 7 fast on the shaft and driven by a belt operated from a countershaft through a treadle-controlled friction clutch. The release of this treadle to allow the clutch to open so that the belt 10 ceases to drive the pulley 7 also throws in mechanism which slows down the main shaft and drives it at low speed backwards to a definite stopping point. The brake and reverse drive mechanism comprises a clutch 15 formed of a member 8 fast for rotation with but slideable along the main shaft, and a member 10 free to rotate on the main shaft but held from movement axially thereof. The latter is continuously driven in a direction reverse to that in which the main shaft rotates during sewing. A cam roll on a lever 12 pivoted on the machine frame is engaged in a cam 14 on the hub of the member 8 and the lever carries in its other arm a recess 16 20 into which a plunger 18 (Figure 1) released (to rise under spring influence) by release of the clutch treadle can spring when the rotation of the shaft 6 brings the recess into proper position. The engagement of the 25 plunger with the recess locks the lever 12 (which has been oscillating idly) and the member 8 is, by the cam 14, forced endwise to close the clutch 8, 10 which first causes a braking effect on the shaft and then a reverse rotation until a definite point is reached 30 when the cam 14 automatically withdraws the member 8. To stop the machine shaft at the desired point, a stop cam 20 is fast on the main shaft and is engaged by a stop arm 22 35 raised into its path when the other arm 24 of the lever of which the stop arm forms part and which is pivoted at 26 is swung rearwardly of the machine on the reversal of the main shaft. This rearward movement 40 is effected by a part 28 pivoted at one end to the arm 24 and having on its other end two segmental surfaces the upper of which, being the nearer to the pivot of this part, normally rests on a sleeve fast on the main 45 shaft. On the reversal of the main shaft a notch in this sleeve acts on the part 28 and rocks it to raise it bringing its other segmental surface against the sleeve and throwing the arm 24 backwards.
- 50 The welt passes to the welt guide at the sewing point round a rotary drum 30 (Figures 3 and 6) to which it is clamped firmly, when the machine is stopped, by a member 32 pivoted to a rotary spindle 34. This 55 clamping is effected by a bell crank lever 36 having the end of one arm engaging the arm 24 and the end of its other arm engaging a yielding plunger 38 (Figure 3). When the 60 welt is thus clamped the withdrawal of the 65 shoe rotates the spindle 34 and raises an

arm 40 fast to it which by connections with a pawl 42 raises the latter to throw into action, as will be described, the welt cutting and welt end holding mechanism, the throwing in of this mechanism thus coming under 70 the control of the operator by movement of the shoe and the amount of welt which can be drawn through the welt guide before severance being definitely determined.

The raising of the pawl 42 allows movement of a roll-carrying ring 44 to close a roll clutch (the ring being urged in this direction by a spring not shown) connecting the member 10 with an eccentric free to rotate on the main shaft and surrounded by a strap 46 connected to mechanism for rotating pinions 48, 50 fast on the same shaft 52 and operating the welt cutting and holding mechanism. A pawl 54 opens the roll clutch after half a revolution of the eccentric so that the welt holding device remains in forward position holding the welt until, at the appropriate time after the recommencement of sewing, a cam 56 lowers the pawl to release the ring 44 to complete its revolution 90 and cause the welt holding mechanism to release the welt and return to normal position.

The welt cutting and holding mechanism comprises two rack bars 58 and 60, the former of which carries the fixed jaw 62 (Figure 4) of the welt holding grippers and has pivoted to it the lower moving jaw 64 and the latter of which carries the cutting knife. The two pinions 48, 50 advance these bars together until the jaws straddle the welt when the pinion 48, which is an interrupted pinion, ceases to operate and the other drives the bar 60 forward relatively to the bar 58 to cause a cam 66 on the bar 60 to close the jaws on the welt and to cause the knife to advance across the jaws to sever the welt. 105

The parts above described may be and preferably are the same, except as herein-after described, as the corresponding parts of the machine illustrated and described in the patent to Topham No. 1,099,326 herein-before referred to, to which reference may be had for a full and complete description of these and other parts of the machine not fully described herein.

In the construction embodying the invention, the pawl 42 is prevented from being lifted during the sewing and, except when the operator depresses a treadle, when the machine is at rest by an adjustable nut and a lock nut 68 on a rod 70 passing loosely through an arm 72 fast to the pawl 42 and having its other end pivoted at 74 to one end of a lever 76 on the same pivot 26 as the stop arm 22. The other end of the lever 76 is pivoted to the upper end of a treadle rod 78.

A stud 80 has pivoted on an eccentric portion thereof 82 a lever 84 having a boss 86 to engage a corresponding boss 88 on the arm 130

24. A tension spring 90 connected at its upper end to the frame of the machine and at its lower end to the lever acts upon the latter to hold the two bosses in contact. In 5 addition this same spring raises the rearward end of the lever 76 to hold the nuts down on the arm 72 and the treadle rod 78 elevated with an adjustable collar 92 thereon 10 elevated with an adjustable collar 92 thereon in contact with the lower surface of an arm 94 fast on the frame and through which it passes. The lower end of the lever 84 during the operation of the machine rests on a surface 96 on the bracket arm 98 and locks the treadle rod against depression, there being 15 a recess at 100 in the arm 98 which allows a limited depression of the treadle rod when the lever 84 is swung to bring its lower end over the recess.

The movable lower jaw 64 of the welt holding device has two welt engaging faces 102 and 104 which are inclined with relation to each other and are continuations of each other, as shown in Figure 4, so that a comparatively thin and narrow welt is gripped to the upper jaw 62 by the face 102 and thicker wider welting is gripped to the upper jaw by the face 104, the jaw 64 being mounted on a pivot bolt or pin 106 for movement independently of an arm 108 (also 20 mounted on the pivot pin 106) which is connected thereto by a torsion spring 110 of substantial length so that the cam 66 on the knife bar 60 acting on a roll 114 mounted on the arm 108 closes the device on welts 25 thus varying in character with a pressure that differs but little in the different cases. The relative masses of the arm 108 and jaw 64 are such that as soon as, in the advance 30 of the bar 58, a face 115 on the arm 108 mounted on the pivot pin 106) which is connected thereto by a torsion spring 110 of substantial length so that the cam 66 on the knife bar 60 acting on a roll 114 mounted on the arm 108 closes the device on welts 35 thus varying in character with a pressure that differs but little in the different cases. The relative masses of the arm 108 and jaw 64 are such that as soon as, in the advance 40 of the bar 58, a face 115 on the arm 108 passes off a cam piece 116 fast on the machine frame the lower jaw moves up to engage the lower surface of the welt, the cam piece being so formed and positioned that this occurs when the bar 58 has advanced 45 just far enough for the tips of the jaws to straddle the narrowest welt likely to be encountered. The mass acting thus to close the jaws on the welt is however so small as in no way to impede the further advance of 50 the jaws across the welt into final position when the advance of the bar 60 causes the cam 66 to depress the roll 114 and, compressing the spring 110 cause the welt to be gripped firmly just prior to the engagement 55 of the cutter with the welt.

It will be understood that it is impossible during the operation of sewing for the welt cutting and holding device to come or be thrown into operation since the pawl 42 is 60 immovably held by the nuts on the rod 70 which is locked against upward movement at this time owing to the lower end of the lever 84 resting on the surface 96. When the machine stops however, and in so doing 65 the cam shaft reverses, the movement of the

arm 24 to the left brings the lower end of the lever 84 over the recess 100 and the welt cutting and holding device can be thrown into operation. This however cannot be brought about by merely drawing the shoe 70 away from the sewing point or by merely depressing the treadle which lifts the rod 70 but both operations have to be performed. Further, to guard against unintentional 75 operation of the latter treadle it is placed at an appropriate distance to one side of the machine starting treadle and on a somewhat higher level. The spring 90 is of such strength as to make it impossible by such pull as can be applied through the welt to 80 raise the pawl forcibly against its resistance.

While it is preferred to employ the specific construction and arrangement of parts illustrated and described, it is to be understood that this construction and arrangement is 85 not essential except so far as specified in the claims, and may be changed or modified without departing from the broader features of the invention.

The nature and scope of the present invention having been indicated and a machine embodying the several features of the invention in their preferred form having been specifically described, what is claimed is:—

1. A welt shoe sewing machine having, in combination, stitch forming devices, power operated mechanism for severing the welt and means dependent for its actuation upon the performance of a plurality of separate operations on the part of the operator after the completion of the sewing operation for controlling the operation of said mechanism.

2. A welt shoe sewing machine having, in combination, stitch forming devices, mechanism for severing the welt, means for throwing said mechanism into operation by movement of the welt while the stitch forming devices are out of operation, and means under the control of the operator for preventing said mechanism from being thus thrown into operation.

3. A welt shoe sewing machine having, in combination, stitch forming devices, power operated mechanism for severing the welt, means for throwing said mechanism into operation and treadle connections operable while the stitch-forming devices are at rest for controlling said means.

4. A welt shoe sewing machine having, in combination, stitch forming devices, treadle connections operable after the completion of the sewing operation and independently thereof, mechanism for severing the welt, and means dependent upon movement of the welt and upon operation of said treadle connections for throwing said mechanism into operation.

5. A welt shoe sewing machine having,

- in combination, stitch forming devices, mechanism for severing the welt, means for throwing said mechanism into operation, treadle connections for controlling said means and means for preventing operation of said treadle connections until after the completion of the sewing operation.
6. A welt shoe sewing machine having, in combination, stitch forming devices, treadle actuated means, mechanism for severing the welt, means dependent upon movement of the welt and upon operation of the treadle actuated means for throwing said mechanism into operation, and means for preventing the operation of the treadle actuated means until after the completion of the sewing operation.
7. A welt shoe sewing machine having, in combination, stitch forming devices, mechanism for severing the welt, means acting upon movement of the welt to throw said mechanism into operation, means for holding said welt from movement while the machine is at rest to prevent said mechanism from being thrown into operation, and means under the control of the operator for releasing said holding means.
8. A welt shoe sewing machine having, in combination, stitch forming devices, a welt measuring device, means for severing the welt thrown into operation by the welt measuring device during the operation of said device in measuring the welt, mechanism for preventing the operation of said device, and means under the control of the operator while the machine is at rest for releasing said mechanism to permit operation of the welt measuring device.
9. A welt shoe sewing machine having, in combination, stitch forming devices, mechanism for severing the welt, means acting upon movement of the welt to throw said mechanism into operation, means comprising a lever capable of being locked in position to prevent said mechanism from being thrown into operation and movable in one direction by the operator independently of the welt to permit said mechanism to be thrown into operation by a movement of the welt, means for locking said lever in position during the normal sewing operation, and means for releasing said locking means upon stopping the machine to permit movement of said lever by the operator.
10. A welt shoe sewing machine having, in combination, stitch forming devices, mechanism for severing the welt, means comprising treadle connections for throwing said mechanism into operation, means for locking said treadle connections out of operation during the normal sewing operation of the machine, and means acting upon stopping the machine to release said treadle connections.
11. A welt shoe sewing machine having,
- in combination, stitch forming devices, power operated mechanism for severing the welt, means for throwing said mechanism into operation upon movement of the welt, and means for preventing said mechanism from being thrown into operation during the normal sewing operation capable of being controlled by the operator after the completion of the sewing operation and independently thereof to permit said mechanism to be thrown into operation.
12. A welt shoe sewing machine having, in combination, stitch forming devices, and power operated means for gripping the welt after the completion of the sewing operation comprising a pair of relatively removable welt gripping jaws, and means for advancing the jaws toward the welt, for partially closing the jaws during said advancing movement and for causing the jaws to grip the welt at the end of the advancing movement.
13. A welt shoe sewing machine having, in combination, stitch forming devices, and means for gripping the welt after the completion of the sewing operation comprising a pair of relatively movable welt gripping jaws, means for advancing the jaws toward the welt, and means for closing the jaws lightly on the outer edge portion of the welt during the advancing movement of the jaws and for causing the jaws to grip the welt at the end of said advancing movement.
14. A welt shoe sewing machine having, in combination, stitch forming devices, and means for severing and holding the welt comprising a reciprocating bar, a pair of welt gripping jaws mounted on the bar, a reciprocating knife carrying bar, means for advancing the jaw carrying bar toward the welt and for partially closing the jaws during the advancing movement, means for advancing the knife carrying bar after the completion of the advancing movement of the jaw carrying bar, and means comprising a cam on the knife carrying bar to cause the jaws to grip the welt during said advancing movement of the knife carrying bar.
15. A sewing machine having in combination, stitch forming devices, and means for severing and holding the welt after the completion of the sewing operation comprising a reciprocating bar provided with a stationary welt gripping jaw, a cooperating welt gripping jaw pivotally mounted on the bar, an arm pivotally mounted on the bar, a torsion spring connecting the arm and pivotally mounted jaw, means for reciprocating the bar to move the jaws toward and from the welt, means cooperating with said arm for opening the jaws during the movement of the bar away from the welt, and for partially closing the jaws during the movement of the bar toward the welt, a knife carry-

- ing bar, means for moving the knife carrying bar toward the welt after the completion of the movement of the jaw carrying bar toward the welt, and means comprising a cam on the knife carrying bar cooperating with said arm to cause the jaws to grip the welt during said movement of the knife carrying bar toward the welt.
16. A welt shoe sewing machine having, in combination, stitch forming devices, and means for holding the welt after the completion of the sewing operation comprising a stationary welt gripping jaw, and a yieldingly actuated pivotally mounted welt gripping jaw having welt engaging surface portions longitudinally inclined with relation to
- 5

each other for cooperating with the stationary jaw to grip welts of different thicknesses.

17. A welt shoe sewing machine having, in combination, stitch forming devices, and means for holding the welt after the completion of the sewing operation comprising a pair of welt gripping jaws pivotally movable with relation to each other, one of which has welt engaging surface portions longitudinally inclined with relation to each other to enable the jaws to uniformly grip welts of different thicknesses.
